PLOW

Hugo E. Pruss, Berkeley, Calif., assignor to Snow Removal Equipment Company, San Francisco, Calif., a firm composed of William B. Vesta, Hugh Jacks, and Lynn Coover

Application November 2, 1936; Serial No. 108,769

14 Claims. (Cl. 37—42)

This invention relates to plows which are attached to and driven by a vehicle, especially to road plows, such as snow plows, but may be applied to ice, dirt or other similar plows. More specifically, the present invention is concerned with an improvement in the attachment for securing the plow and its supporting frame to a vehicle, such as a motor truck or tractor. It is particularly applicable to plows which are detachably secured to motor vehicles, but is also applicable to permanent installations.

It is known to attach a plow frame to a vehicle by means of a pivot fixed to a part of the vehicle, such as a truck axle, whereby the plow can be swung upwardly to adjust the height of the plow blade in relation to the ground, and the depth to which the cutting edge enters the snow or soil may thereby be controlled and the plow placed into and out of operation. Such a construction is, for example, described in the United States patent to Hewitt, No. 2,055,794. In such a device the weight of the plow share or blade, as well as of the forward end of the frame, is carried by running devices, such as one or more wheels or sleds, attached to the forward end of the frame, and the frame functions mainly to transmit a horizontal force to push the plow into the material to be excavated, and to steer it in the desired direction. While it is customary to mount the blade in front of the vehicle, it may also be mounted in rear of it.

The horizontal thrust carried by the frame in such constructions is considerable, and it has been necessary to provide a pivot bearing and a frame structure of generous dimensions to insure the life of the bearing and to prevent buckling of the frame.

In such a construction, moreover, the frame is rigidly pivoted to the vehicle, so that whenever the vehicle is tilted laterally the plow is similarly tilted. This may occur, for example, when one tire is larger than the other tire on the same axle, or when one wheel passes over an obstruction, or enters a depression, or, when clearing snow or other material from a roadway, when one side of the truck is off of the pavement. The tilting of the plow frame prevents the plow from digging into the soil or snow to the desired uniform depth along all points of the plow blade, and places a great twisting stress on the frame structure, especially when a plurality of runners is employed, one of the runners being frequently lifted off the ground or snow surface. Similarly, when the one of a plurality of supporting runners rides over an obstruction, the other will be lifted off

the ground. These difficulties are encountered in plows which are mounted perpendicular to the longitudinal axis of the vehicle as well as in plows which are mounted diagonally with respect to the said axis.

This difficulty has, in the past, made it impractical to mount the plow frame to a sprung chassis, which is often subject to tilting with respect to the ground, due to swaying or unequal loading, necessitating the fastening of the pivot and frame to the axle of the vehicle. Such a mounting is, however, undesirable because it places an undue stress upon the truck axle and the bracing structure which holds the axle in alignment to the truck, and because insufficient space is available near the axle for providing pivots and frame members of the necessary strength.

A further difficulty encountered in such constructions, and particularly in connection with plow blades which, like that shown in the Hewitt patent, above referred to, are disposed diagonally with respect to the axis of the vehicle and the axis of the pivots, is that when the height of the plow is adjusted with respect to the ground or snow surface, both ends of the plow blade cannot be made to rise the same distance. This is due to the fact that both ends of the blade are pivoted about the same pivot axis so that the end of the plow the farthest removed from the vehicle, due to its longer radius, swings through a greater vertical distance than the other end of the blade. If, for example, the rearward runner of such a push plow employed to remove snow passes over a mound of snow and is thereby lifted, the leading runner, instead of remaining on the surface, will be lifted through a vertical distance which is greater than the lift on the rearward runner, placing a torsional stress on the frame and preventing effective removal of snow from the area traversed by the leading end of the blade. Similar difficulty is encountered when the blade is intentionally raised or lowered.

Still another difficulty encountered in plows which are diagonally mounted with respect to the vehicle and frame is that the forward end of the frame can be maintained in its proper vertical position with respect to the ground or snow only when the pivot axis on the truck is at the correct height above the ground. When the tires on the truck are changed, or when the truck moves over rough ground, the axle or chassis frame is higher or lower than the height for which the frame was designed, and the difficulties described in the preceding paragraph are also encountered. This circumstance, moreover, makes it impossible to

attach the plow frame to a vehicle other than the one for which it was constructed.

Broadly, the present invention contemplates the provision of a novel and improved plow frame particularly adapted to be attached to a vehicle which is capable of moving the plow forwardly and maintaining it in its proper direction of travel, while permitting the plow to assume its proper positioning with respect to the ground or snow surface irrespective of the height or lateral inclination of the vehicle or the relative vertical position of the supporting runners.

It is an object of the invention to provide an improved means for attaching a plow frame to a vehicle which may be attached to a sprung portion, as well as to an unsprung portion of the vehicle, and which will permit the vehicle to move over rough and irregular ground. It is a further object to provide a novel and improved attaching means which will permit the plow to be attached to vehicles of different heights above the ground, and to operate efficiently regardless of variations in the height of the vehicle axle or chassis with respect to the ground.

25 A further object of this invention is the provision of a means for attaching the plow frame to a vehicle in a manner which will permit the end of the frame nearest the vehicle (either forwardly or rearwardly) to have a constrained vertical movement with respect to the vehicle. A further object is to provide a plow frame which is better able to transmit horizontal thrust to the vehicle and have a lesser tendency to buckle than the frames heretofore employed.

35 Still another object of the invention is the provision of a plow frame having a diagonally disposed plow blade which may assume its proper position with respect to the ground or surface of the snow, irrespective of the lateral inclination of the portion of the vehicle to which the frame is secured. A further object is to provide a plow frame which may be attached to a vehicle so as to have free lateral tilting and vertical as well as vertical tilting movements with respect to the vehicle.

The above and additional objects, which will hereinafter be more specifically treated, are attained by such means as are shown in the accompanying drawings, described in the following specification, and more clearly pointed out in the claims. While I have in the following specification described only four specific embodiments of the invention, and have described these with sufficient detail to enable those skilled in the art to which it pertains to understand the mode of construction and the principles involved, it is to be understood that there is no intentional limitation to the specific forms and precise details shown, and that various modifications of the same can be resorted to without departing from the spirit and scope of the invention, and without sacrificing the benefits derivable therefrom. It is also to be understood that certain features of the invention herein disclosed may be employed in and with other combinations than those shown and described.

70 The invention will be described as applied to a snow plow of the general type shown in the Hewitt patent, above referred to, it being understood that it may be employed in connection with the rotor shown therein, or without it, and that persons skilled in the art of excavating can make such modifications as are necessary to adapt the invention to other purposes. In the 75 drawings:

Figure 1 is a fragmental side elevation of a snow plow comprehending the present invention, as it would appear when operatively connected to its correlated automotive vehicle, the plow blade being shown partly in section.

Figure 2 is a top plan view thereof.

Figure 3 is a horizontal section taken on line 3—3 of Figure 1, illustrating the mounting of the frame to the transverse girder or bolster.

Figure 4 is a transverse section taken on line 10 4—4 of Figure 3 in the direction of the arrows.

Figure 5 is an elevation view of a pump employed to operate the lifting ram.

Figure 6 is an enlarged fragmentary perspective view illustrating the preferred mode of supporting the transverse bars and girder on the side abutment plates which are attached to the vehicle.

Figure 7 is a transverse section taken on line 7—7 of Figure 2, illustrating the mounting of 20 the transverse girder.

Figure 8 is a fragmentary side elevation of a modification of a portion of the frame and attaching means.

Figure 9 is a horizontal section taken on line 25 9—9 of Figure 8.

Figure 10 is a fragmental horizontal sectional view, partly in elevation, similar to Figure 3, showing a further modification of my invention.

Figure 11 is a transverse section taken on line 30 11—11 of Figure 10 in the direction of the arrows.

Figure 12 is a horizontal vertical view taken on line 12—12 of Figure 10.

Figure 13 is a fragmental horizontal sectional 35 view, partly in elevation, similar to Figure 3, showing still another modification of my invention.

Figure 14 is an end view of the construction shown in Figure 13.

Referring to the drawings, and particularly to Figures 1 to 7 thereof, 10 is the sprung chassis of an automobile or similar vehicle, which may be provided with springs, not shown, and having an engine compartment 11 and wheels 12. 40 A pair of abutment plates 13—13' is secured to the chassis by detachable bolts, as shown. The abutment plates are spaced apart and rigidly connected by a pair of transverse channel bars 14—14', with vertical webs, and a third channel bar 15, welded or otherwise secured to the inner faces of the plates 13—13'. The bars 14—14' are provided with a removable pin or bolt 16, braced by a bushing 17, and forming a trunnion rotatably supporting a tiltable bolster 18, located between the bars 14, and extending through notches 13a, cut in the plates 13—13' (see Figures 6 and 7). The notches have vertical dimensions to permit the bolster 18 to tilt in a vertical plane about the pin 16 through an arc 50 of about 10 to 15 degrees on either side of horizontal. The vertical faces of the notches are smooth, and are preferably provided with bearing surfaces by welding face plates 19—19' thereto (see Figures 3, 6, and 7). The plates 55 19—19' are located to engage the forward and rear edges of the bolster 18, so as to prevent its rotation about a vertical axis, thereby forming abutment means to transmit longitudinal stress from the chassis 10 to the bolster. 60

A rigid tower 20 is mounted on the abutment plates 13—13', braced by tie rods 21—21', and provided with resilient supporting means and hoisting means, hereafter described.

The details on each end of the bolster 18 are 75

similar, and only one will be described in detail. Fixedly attached to the end of the bolster 18 is a circular disc or journal 22, revolvably housed in a bearing member 23. The bearing member 23 is fixed to a plate 24, shaped to provide a vertical groove on its outer face. A vertically elongated bar 25 is slidably mounted in the groove and has a small amount of free play in its groove; it extends both above and below the plate 24.

Fixedly secured to the bars 25 (one on each end of the bolster 18) is a pair of forwardly extending struts 26-26' forming the side members of the plow supporting frame. A plurality of holes 27 is provided in the bars 25 for receiving an adjustable pin 28, adapted to rest on the upper edge of the plate 24 to limit the downward movement of the bar 25 in its groove. A second pin 29 may, if desired, be similarly inserted in a hole below the plate 24 to limit the upward travel. If desired, the pins 28 and 29 may be located so as entirely to prevent a sliding motion.

The struts 26 may be suitably reinforced against buckling, and provided with a transverse bar 30. The forward ends of the struts are curved to fit the rear surface of a plow blade 31, to which they may be fixedly secured, as shown, but to which they may be attached in the manner illustrated in Figures 1 to 3 and 7 of the Hewitt patent, referred to above. The weight of the forward end of the frame and the blade 31 is supported by means of runners 32-32' (which term is intended to include skids, wheels, sleds, etc.). A convenient manner of attaching the runners is to weld vertical ribs 33-33' to the rear surface of the blade 31, and to secure the runners to these ribs by means of adjusting bolts 34 and clamping bolts 35.

A hydraulic or oil ram 36 is suspended from the tower 20 and secured to ribs 37-37' carried by and extending rearwardly from the blade 31. The midway point between the ribs 37-37' is generally off-center, and located so as to balance the weight of the frame and plow when the same are swung upwardly about the journals 22 to place the plow out of operation, or, during operation, to elevate the blade to clear an obstruction or to make a shallower cut into the snow.

The ram 36 may be operated by a hand or motor driven pump 38, preferably operable or controllable from the driver's compartment of the truck, and connected to the ram by means of fluid pressure transmitting tubing 39. The ram and its attaching means are so constructed as to permit the frame to be tilted upwardly through an angle of about 30 degrees above horizontal. While the ram may be employed to raise the blade during operation as stated above, it normally supports no weight when the plow is resting on the runners 32-32'.

According to the novel means for supporting the plow and its frame when in operation contemplated in one embodiment of the present invention, the weight of these parts is carried by three points: The two runners 32 and 32' support the weight of the front portion of the structure; the rear portion of the frame is supported from the tower 20 by a cable 40 which is preferably provided with a turnbuckle 41 and a coiled spring 42 or similar resilient means for restrainingly supporting the rear end of the frame; but the resilient spring may, if desired, be omitted. The point of attachment of the cable 40 is generally off-center, and is preferably so chosen,

and the length of the cable and the stiffness of the spring are such, that the weight of the rear end of the frame is balanced with respect to the runners 32-32'. In this manner no weight is, during the normal operation, carried by the pins 28 and 29, these pins serving merely as safety devices to hold the bars 25 in the groove on the plate 24, when the frame and blade are swung upwardly by the action of the ram 36; the pins may be omitted entirely. By the action of the resilient spring 42 the rear end of the frame has a restrained vertical movement with respect to the truck and flexibility and stability are insured. The three point support, moreover, (whether or not the cable 40 is provided with a resilient means) makes it possible for both of the runners 32-32' to be in contact with the ground or snow surface, regardless of the relative elevations of the surface supporting these runners, and irrespective of the lateral tilting of the truck.

If, for example, the truck is tilted laterally with respect to the runners or the frame, the frame is free to turn about a substantially longitudinal axis, being supported only by the cable 40. The struts 26, being a part of the frame, will in this case transmit the transverse turning motion to the bolster 18 by means of the bearings 23 and journals 22; but this bolster is free to pivot about the trunnion pin 16 and torsional stresses in the frame are prevented.

It should be noted that the cable 40 is not indispensable, inasmuch as the weight of the rear end of the frame can also be supported by the ram 36, which may be attached to the frame at a point to adapt it to perform both the function of lifting the frame about the journals 22 when it is desired to swing the blade 31 upwardly, and the function above described for the cable 40. Finally, it is also possible to dispense entirely with a pendant suspension means for the rear end of the frame during the normal operation (thereby eliminating the cable 40 and either eliminating also the ram 36 and tower 20, or employing the latter only for swinging the frame upwardly) and to carry the weight of the rear end of the frame by means of the pins 28, journals 22, and the trunnion pin 16, in which case the pin 16 will function as the third point of support and a three point of suspension will be realized.

It should also be noted that the relative vertical sliding motion between the bar 25 and the plate 24 improves the flexibility of the device, particularly when the cable 40 is employed, since it prevents the transmission of a substantial amount of vertical thrust from the frame to the bolster 18 and the motor vehicle. This relative sliding movement is also of advantage whether or not the cable 40 is employed, since it permits the abutment plates 13-13' to be attached to motor vehicles of different heights without requiring a reconstruction of the frame and struts 26, the pins 28 and 29 being merely inserted into the proper holes. The sliding motion is, however, not indispensable to the operativeness of the device, inasmuch as it is possible to carry the weight of the rear end of the frame by the trunnion pin 16, as pointed out above, and yet prevent torsional stresses in the frame. In this case the struts 26 may be fixedly attached to the plates 24 or the pins 28 and 29 may be adjusted to prevent a relative vertical sliding movement between these parts.

During the operation of the plow the horizontal

stress is completely transmitted from the frame by its struts 26 to the bolster 18 and from the bolster 18 to the abutment plates 13-13' by the abutment of the front and rear edges of the bolster on the vertical faces of the notches 13a in the plates 13-13'. This arrangement at the same time maintains the frame in the proper directional alignment with respect to the vehicle. Since the vertical edges of the notches in the plates 13-13' carry considerable stress it is desirable to reinforce these plates and, moreover, to increase the rubbing surface beyond the thickness of the plates. This may be effected either by mounting the bars 14-14' so close together that the bolster bears against their inner faces, or by attaching the smooth face plates 19-19' on the vertical edges of the notches 13a, as described above.

When it is desired to detach the plow and frame from the vehicle it is only necessary to pull out the pins 16 and 29 and to disconnect the cable connections depending from the tower 20. The bolster 18, together with the journals 22, bearings 23, and plates 24, may then be slid downwardly and out of engagements with the plates 13-13' and the bars 25. Alternatively, the pins 16 may be left in position and only the pins 29 removed, the struts 26 and the bars 25 being then lifted out of engagement with the plates 24. The plates 13-13' may then be readily unbolted from the truck chassis. It will be noted that the frame is very rapidly and easily attached to and removed from the vehicle. If desired, the plates 13-13' may be left on the vehicle during the winter season, thereby still simplifying the operation of placing the plow into operative order. Moreover, the plates 13-13' and its tower may be employed with a dirt plow in certain seasons, and with a snow plow in other seasons.

In the slightly modified form of the attaching means shown in Figures 8 and 9 the struts 26 are further braced against buckling and the stress on the journal is reduced materially. In these figures parts corresponding to those described above in connection with Figures 1 to 7 are indicated by like reference numerals. The abutment plate 13, its face plates 19-19', the bolster 18, the plow frame and its supporting runners and cables are each similar to those of Figures 1 to 7. A vertically elongated bar 44 is fixedly attached to each end of the bolster 18, and is provided with a plurality of holes 45. A slide 46 having inwardly projecting guides 47-47' and flanges, as shown, is arranged to have a vertical sliding motion with respect to the bar 44. The vertical dimension of the slide 46 is less than that of the bar 44, and the vertical movement of the slide 46 may be limited or prevented by means of pins 48 and 49 which may be inserted into the holes 45.

The outer face of the slide 46 is provided with a journal or pin 50, passing through a horizontally elongated hole or slot 51 in the thrust member 52. The member 52 is fixedly attached to the strut 26 or may be formed integrally therewith. The plate 26 is attached to the plow blade at its forward end as shown in Figures 1 and 2. The inner face of the member 52 is provided with an arcuate flange 53 having its center of curvature at the center of the journal 50. A coacting arcuate flange 54 is formed on the slide 46 and is shaped to fit the inner face of the flange 53. The slide 46, together with the flange 53, constitute a second thrust member.

Since the slot 51 extends longitudinally with

respect to the member 52, it will maintain the member 52 in its proper vertical position with relation to the slide 46; but horizontal thrust is carried entirely by the contacting faces of the flanges 53 and 54. As a result of these flanges 53 and 54, the stress on the journal is greatly reduced, and the length of the member 52 through which the horizontal stress is carried is shortened, thereby reducing the tendency to buckle. Moreover, the flange 53 has an appreciable vertical dimension 10 and the member 52 can, therefore, be more easily reinforced to transmit horizontal force.

The modes of operation of the embodiment illustrated in Figures 8 and 9 are similar to those described above in connection with Figures 1 to 7. It should, however, be noted that the coacting arcuate flanges may also be employed in connection with other forms of plows which do not comprise the tilttable bolster and/or the vertical slide. Thus, the thrust member 46 carrying the journal 50 and the flange 54 may be attached directly to the chassis of a vehicle.

In the modification illustrated in Figures 10, 11, and 12, the bearings and journals 22 and 23 are eliminated by employing a circular transverse bolster 55 rotatably mounted in slides 56-56'. The slides 56-56' are mounted to engage the vertical edges of a notch 57a formed in abutment plates 57-57', which are similar to the abutment plates 13-13' shown in Figures 1 to 7, and which may be similarly attached to the chassis of the vehicle and similarly braced by channel bars 58-58'.

The bolster 55 may be retained by means of a pin or trunnion bolt 59 extending between the bars 58-58' and through an elongated hole 60 in the bolster 55, the hole being shaped to permit the bolster to rotate about its axis through an arc of about 30 degrees or less. The bolster is laterally tiltable about the pin 59 through an arc 40 of about 10 to 15 degrees on either side of horizontal. The slides 56-56' are thereby prevented from moving out of the notches.

The slides 56-56' are provided on their front and rear faces with a pair of grooves 61-61' to receive the walls of abutment plates 57-57'. The bottoms of the grooves are plane surfaces spaced so as to engage the vertical edges of the notch 57a (see Figure 11); the side faces of the grooves are curved, as shown in Figure 12, to engage the side walls of the plates 57-57' when the bolster is tilted laterally about the pin 59.

A vertically elongated bar 62 is fixedly attached to each end of the bolster 55, and provided with a plurality of holes (not shown, but similar to the holes 45 in the bar 44 shown in Figure 8). A slide 63, having inwardly projecting guides 64-64' and flanges, as shown, is arranged to have a vertical sliding motion with respect to the bar 62. The vertical dimension of the slide 63 is less than that of the bar 62, and the vertical movement of the slide 63 may be limited or prevented by means of pins 75, as described above in connection with Figures 8 and 9. Struts 65-65' (corresponding to the struts 26-26' shown in Figures 1 to 7) are fixedly secured to the slides 63, and form the sides of the plow frame.

The modes of operation of the embodiment illustrated in Figures 10, 11, and 12 are similar to those described in connection with Figures 1 to 7. When the plow frame is swung upwardly to clear an obstruction or to place the plow out of operation the bolster 55 rotates in the slides 56-56' and about the pin 59. Otherwise the function of the device is identical, i. e., it may be supported

by the cable 40, or the weight of the rear portion of the frame may be carried by the trunnion pin 59.

In the embodiment shown in Figures 10, 11, and 12 the downward movement of the slides 56—56' may be limited by stirrups 71 attached to the plates 57—57' as shown, and the endwise movement of the bolster 55 in the slides may be limited by means of pins 66—66'. (A limited endwise motion is necessary.) When these added features are provided, the trunnion pin 59 may in certain cases be omitted.

According to the fourth modification, shown in Figures 13 and 14, a bolster in the form of a continuous transverse girder may be omitted. In these figures, abutment plates 61—61', carried by the chassis of the vehicle, are provided with slides 68—68' and with stirrups 69 to limit the downward movement of the slides, all as shown in Figures 10, 11, and 12. Rotatably mounted in each slide 68 is a heavy bolster pin 70, provided with a nut 72 to have a limited endwise motion. Struts 73—73', forming the side plates of the plow frame, and corresponding to the struts 26—26' of Figures 1 to 7 are fixedly secured to the pins 70.

In this modification, the frame may be swung upwardly by rotation of the pins 70 in the slides 68—68'. These slides may float between their upper and lower positions when the rear end of the frame is supported by the cable 40; when this is not employed, they may rest on the stirrups 69, which may be provided with an adjustable bolt 74 to limit the downward movement. When the plow frame is tilted laterally one slide moves vertically with respect to the other, thereby preventing torsional stress in the frame, and maintaining the plow blade in its proper position with respect to the ground.

40 I claim as my invention:

1. The combination with an automotive vehicle of a transverse bolster attached to said vehicle rotatable in a substantially vertical plane transverse to the vehicle and secured to transmit longitudinal thrust to said vehicle, a plow frame extending longitudinally from one end of said vehicle having a plow attached thereto at one end thereof, slide means interposed between the other end of the frame and said bolster arranged to permit said other end of the frame to be adjusted vertically with respect to said bolster, means to lock said slide means in an adjusted position, said bolster being arranged and constructed to permit said frame to be swung upwardly about a horizontal transverse axis at the second end of the frame.

2. The combination according to claim 1 in which the bolster is supported at a point intermediate its ends by a trunnion pin disposed longitudinally with respect to said vehicle.

3. The combination according to claim 1 in which the said second end of the frame is non-pivotally attached to the bolster by the said slide means, and the bolster is rotatable about its own axis.

4. The combination according to claim 1 in which the frame is rotatable with respect to the bolster about an axis substantially parallel to the axis of the bolster.

70 5. The combination with an automotive vehicle of a transverse bolster attached to said vehicle so as to be rotatable in a substantially vertical plane transverse to the vehicle and to transmit longitudinal thrust to said vehicle, a plow frame extending longitudinally from one end of

said vehicle having a plow attached thereto at one end thereof, and a pair of struts extending to the other end, slide means interposed between said struts and said bolster arranged to permit said struts to be moved vertically with respect to said bolster, said slide means comprising two juxtaposed vertically extending members, a plurality of perforations in at least a first of said members, and removable pin means extending through said perforated first member engageable with the second member to limit the vertical movement between said members, whereby the height of said struts with respect to the bolster may be adjusted.

6. A plow comprising a pair of laterally spaced abutment plates and an intermediate longitudinally disposed trunnion adapted to be attached to a motor vehicle, a transverse bolster rotatable about its own axis and pivoted about the trunnion axis, and a plow frame mounted upon said bolster, each of said abutment plates being provided with a substantially vertical face near said bolster and in thrust transmitting relationship thereto, whereby longitudinal thrust from said plow frame may be transmitted through said bolster to said abutment plates.

7. A plow comprising a pair of laterally spaced abutment plates and an intermediate longitudinally disposed trunnion pin adapted to be attached to a motor vehicle, a transverse bolster, a longitudinal, vertically elongated hole in said bolster, said trunnion pin passing through said hole, whereby said bolster is supported and is rotatable about its own axis and pivoted about the axis of the trunnion pin, each of said abutment plates being provided with a substantially vertical face near said bolster and in thrust transmitting relationship thereto, whereby longitudinal thrust from said plow frame may be transmitted through said bolster to said abutment plates.

8. A plow comprising a pair of laterally spaced abutment plates and an intermediate longitudinally disposed trunnion adapted to be attached to a motor vehicle, a transverse bolster rotatable about its own axis and pivoted about the trunnion axis, a plow frame mounted upon said bolster, each of said abutment plates being provided with a substantially vertical face, and a slide near each end of said bolster revolvably housing the same and in sliding engagement with faces in said abutment plates, whereby longitudinal thrust from said plow frame may be transmitted through said bolster and slides to said abutment plates.

9. The combination with an automotive vehicle of a pair of spaced plates attached to the frame of said vehicle, said plates having vertically disposed notches, a bolster extending transversely with respect to said vehicle and through said notches, mounted to be rotatable about the longitudinal axis of said vehicle and to slidably engage the vertical edges of said notches, a plow frame having a pair of side members, pivot means for connecting one of said side members to each end of said bolster, whereby said frame may be swung about the axis of said bolster, and a plow blade attached to the end of said frame remote from said bolster.

10. The combination with an automotive vehicle of a pair of spaced plates attached to the frame of said vehicle, said plates having substantially vertically disposed edges, a vertically movable slide on each of said side plates engaging said edges, a bolster extending transversely

with respect to said vehicle rotatably mounted in said slides, a plow frame having a pair of side members, means for attaching one of said side members to each end of said bolster, and a plow 5 blade attached to the end of said frame remote from said bolster.

11. The combination with an automotive vehicle of a pair of spaced abutment plates attached to the frame of said vehicle, said plates 10 having substantially vertically disposed edges, a bolster extending transversely with respect to said vehicle mounted to be rotatable in a substantially vertical plane transverse to said vehicle and to transmit longitudinal thrust to the 15 vertical edges of said abutment plates, a plow frame having a first thrust member extending forwardly from said vehicle on each side of the frame, a plow blade attached to the forward end of said frame, and means at each end of said 20 bolster for rotatably connecting the rear end of said frame about a pivot axis substantially parallel with the axis of the said bolster comprising a second thrust member carried by said bolster and extending forwardly from said pivot 25 axis, a pin substantially at said pivot axis carried by one of said members and extending through a longitudinally elongated slot in the other of said members, a first arcuate flange carried by said first thrust member having its center of 30 curvature at said pivot axis, and a second arcuate flange on said second thrust member in engagement with said first flange, disposed so as to transmit longitudinal force from said plow frame to said second thrust member between said 35 flanges.

12. The combination with an automotive vehicle of a plow frame having a first thrust member and extending forwardly from said vehicle, a plow blade attached to the forward end of said 40 frame, and means for rotatably connecting the

rear end of said frame to the vehicle about a pivot center comprising a second thrust member carried by said vehicle and extending forwardly from said pivot center, a pin substantially at said pivot center carried by one of said members and extending through a longitudinally elongated slot in the other of said members, a first arcuate flange carried by said first thrust member having its center of curvature at said pivot center, and a second arcuate flange on said second thrust member, in engagement with said first flange, disposed so as to transmit longitudinal force from said plow frame to said second thrust member between said flanges. 5 10

13. The combination with an automotive vehicle of a plow frame movably attached to one end of said vehicle and extending forwardly therefrom, thrust transmitting means for transmitting longitudinal force from the frame to said vehicle, a plow blade mounted at the forward end 20 of said frame diagonally with respect to the axis of said vehicle, a plurality of spaced runners near the forward end of said frame for supporting the plow with respect to the ground, and supporting means attached to the vehicle forming 25 a single point vertical support for the rear end of said frame comprising a bolster fixed to the rear end of the frame and disposed transversely with respect to said vehicle, a longitudinal, vertically elongated hole at an intermediate point in 30 said bolster, and a longitudinally disposed trunnion pin carried by said vehicle passing through said hole, whereby said bolster is supported by said trunnion pin and may rotate about the trunnion axis and about its own axis. 35

14. The combination according to claim 13 in which the bolster is adjustably secured to said frame by means permitting vertical adjustment between the bolster and the frame.

HUGO E. PRUSS. 40
